UNITED STATES PATENT OFFICE.

THOMAS LUND, OF BEVERLY, MASSACHUSETTS, ASSIGNOR TO UNITED SHOE MACHINERY CORPORATION, OF PATERSON, NEW JERSEY, A CORPORATION OF NEW JERSEY.

MACHINE FOR OPERATING UPON HEELS.

Application filed June 12, 1919. Serial No. 303,698.

To all whom it may concern:

Be it known that I, THOMAS LUND, a citizen of the United States, residing at Beverly, in the county of Essex and State of Massachusetts, have invented certain Improvements in Machines for Operating Upon Heels, of which the following description, in connection with the accompanying drawings, is a specification, like reference 5 characters on the drawings indicating like parts in the several figures.

This invention relates to machines for performing a plurality of operations upon heels. The invention is herein set forth by 15 way of illustration with special reference to its applicability to compressing and breasting heels before they are attached to their shoes.

Until recently it has been a universal 20 practice in this country to breast the heels of shoes after they were attached. Now, however, the practice of breasting heels before their attachment is becoming increasingly prevalent. Since practically all heels, 25 the breasts of which are straight in the direction of the height of the heel, are compressed, it is advantageous to perform the breasting operation in conjunction with the compressing operation. Accordingly, an 30 object of this invention is to provide a machine which will automatically compress and breast heels.

A feature of the invention consists in an 35 organization comprising means for removing surplus material from a heel and compressing the heel, in combination with operating means to effect said treatments of the heel in succession. As herein shown the heel is operated upon at successive stations, 40 and means comprising a carrier, which may be intermittently rotatable, is operated in time relation to the said means to effect progression of the heel from one to the other of said means. As is usual in well-known heel 45 compressing machines, as shown, the side dies of the relatively movable heel compressing means move vertically, and the toplift plate moves relatively to the compressing means to eject the heel or to cause it to be 50 presented after compression above the compressing means. To provide effective co-operation with the compressing mechanism, the illustrated heel transferring means,

herein shown as comprising co-operating fingers, is operated horizontally to take the heel from the position in which it is presented by the toplift plate or ejector and to carry it to another position for another operation. Preferably the transferring means 55 presents the heel in predetermined operative relation to a second transferring means 60 which is intermittently operated and may comprise, as shown herein, a rotatable or endless carrier having a series of pairs of jaws movable over a relatively fixed table 65 upon which the heel is located by the first transferring means, a pair of jaws being closed upon the heel and moved to another position in operative relation to the breasting means which, as shown, comprises a reciprocating knife acting in the direction of 70 the height of the heel.

A further feature of the invention consists in means for automatically locating a 75 shoe bottom blank, or example an unattached heel, in a predetermined position both longitudinally and rotationally, that is, about an axis lying within the body of the blank and perpendicular to its larger 80 flat faces. Such means may consist in positioning members relatively power operated in the operation of the machine and acting on the blank to determine both its longitudinal position and orientation, that is, to effect a rotational movement of the blank 85 in its own plane so as to locate its longitudinal median line in a predetermined direction. The blank is thus accurately located for a subsequent operation on the blank and in the exemplary embodiment of the invention illustrated a heel blank is positioned 90 in a plane parallel to the plane of the table so that the breast face will be parallel with the knife edge. As shown herein, the positioning means comprises a striker which is 95 actuated to engage the heel during operative movement of the knife and which is held out of operative position during the return movement of the knife. Preferably and as shown, the operation of the striker is controlled by the knife slide during the operative movement of the knife.

Another feature of the invention consists 100 in means on the table corresponding in curvature to the transverse contour of the knife 105 and co-operating with the knife to effect a

shear cut upon the heel. Preferably said means is formed as a block which may be detached from the table when a differently curved knife is to be used and another block 5 substituted therefor which corresponds to the curve of the new knife. Also, as shown, the block is arranged for adjustment transversely of the knife to enable its co-operating face to be set in accurate relation to the 10 knife.

A further feature of the invention consists in novel mechanism for releasing the intermittently movable jaws to allow them to seize the heel or to open them to allow 15 the heel to fall out after the breasting operation is completed. Preferably at the point where the jaws are opened to release the breastested heel the table that supports the heel is cut away to allow the heel to fall 20 from the jaws.

Another feature of the invention consists in means for holding an unattached heel in a fixed position and means for effecting two 25 strokes of the breasting knife while the heel is so held. The first stroke breasts the heel by making a roughing cut while the second stroke effects a finishing cut which smooths the breast face.

These and other features of the invention, 30 including novel means for holding the heel, for controlling the opening and closing of the jaws, and various details of construction and combinations of parts, will appear more fully from the following detailed description 35 when read in connection with the accompanying drawings and will be pointed out in the appended claims.

The heel compressing mechanism herein shown by way of illustration is similar to, 40 that disclosed in prior Letters Patent of the United States No. 1,172,471, granted February 22, 1916 on my application.

In the drawings,—

Fig. 1 is a side elevation, partly in section, 45 of a machine embodying this invention;

Fig. 2 is a detail, in plan, of parts shown in Fig. 1;

Fig. 3 is a rear elevation of the machine, 50 certain parts being omitted for the sake of clearness of illustration;

Fig. 4 is a detail, in elevation, of parts partly shown in Fig. 3 and taken on the opposite side from Fig. 3;

Fig. 5 is a sectional detail of the breasting 55 mechanism;

Fig. 6 is a plan view, partly in section, 60 certain parts, including the breasting mechanism being omitted;

Fig. 7 is an enlarged detail of parts shown in Fig. 6;

Fig. 8 is a detail of mechanism for imparting intermittent movement to the heel jaws;

Fig. 9 is a detail, in elevation, of the stop 65 for opening the jaws to release the heel;

Fig. 10 is a sectional detail of one of the friction pivots shown in Fig. 4;

Fig. 11 is a perspective view of a washer shown in Fig. 10; and

Fig. 12 is a detail of the jaw opening 70 cam.

In Fig. 1 of the drawings the numeral 1 indicates the rigid frame of the machine on which the mechanism is supported. Vertical guideways are provided in the sides of 75 the rigid frame and a head 2 is mounted therein for reciprocation. A suitable driving pulley and reducing mechanism are provided as shown in my prior patent above referred to, for transmitting motion to a gear 80 on a crank shaft 9. A link 10 is connected to the crank shaft 9 and also to a toggle composed of members 11 and 12. The toggle member 11 is pivoted to a rigid portion of the frame near its base and the other 85 toggle member 12 is pivoted at 14 to the reciprocating head 2. The head carries a heel mold comprising a toplift plate 40, a breast die 21, and laterally movable side compressing dies 22, as shown in Figs. 1 90 and 6.

In the upper part of the machine frame and aligned with the reciprocating head 2 is formed a rigid abutment 23 upon which is detachably mounted a heel seat die 25 in 95 position to co-operate with the mold members carried by the head 2. The side compressing dies rest on the top of the head 2 and are removably retained in slides 30 in order that other dies of different shapes 100 may be substituted in changing from one style of heel to another. The side compressing dies 22 and breast plate 21 are actuated to close the mold and are thereafter opened to release the compressed heel by any desired mechanism, for instance, by normally inclined links 17 pivoted on opposite sides of the machine frame at 18, 18 as shown in Fig. 6.

The toplift plate 40 is provided with a 110 downwardly extending stem 41 and mechanism is provided such, for instance, as that shown in my prior patent above referred to, for moving the toplift plate relatively to the mold, as shown in Fig. 1, so as always 115 to present the heel with its lower or toplift face flush with the upper surface of the mold.

The heels are fed to the compressor at the left of Fig. 1, each heel being positioned between fingers 31 (Fig. 6) with its breast face against a breast gage 33, the fingers being then in open position and the mold closed. As the head 2 moves downwardly and with it a frame 35 on which a lever 37 120 is carried, the lever 37 is actuated by connections shown in Fig. 1 to move the fingers and heel over the now open mold, the fingers 125 being separated to release the heel by the action of a stationary cam 39 acting upon an 130

outward projection 43 of one of the fingers 31. This feeding mechanism is well-known in heel compressors and is substantially as shown and described in my prior patent 5 above referred to.

The mechanism for transferring away from the compressor the heel which is ejected after compression by the toplift plate 40, will now be described and comprises mechanism best shown in Figs. 1 and 6. As shown in Fig. 6, the mold slides 30, which are connected to the links 17 and through which pressure is applied laterally to the mold members 22, 22, are provided with grooves 10 32 preferably dovetailed in which are mounted sliding blocks 34. Fingers 36 are pivoted to the blocks at 38 and are shaped as shown in Fig. 6. To each finger, at a point outside of the pivot 38, is pivoted a member 42 by a vertical pivot 44. Links 46 are pivoted by horizontal pivots 48 to the members 42, and means to be described is provided for moving the links 46 lengthwise to operate the fingers. The pivots 44, 48 15 provide universal joint connections between the links 46 and the fingers 36. Movement of the links 46 toward the heel compressor first causes the fingers 36 to separate sufficiently to clear the heel and the feed fingers 31 and then moves the slides 34 with the fingers 36 lengthwise of the heel in the compressor until the fingers are behind the heel, the feed fingers 31 being at the same time retracted. The motion of the links 46 is 20 then reversed, causing the ends 47 of the fingers 36 to close against the heel. Lugs 50 on the fingers then engage the breast face of the heel and further movement of the links causes the fingers to transfer the heel 25 from the heel compressor into a predetermined position upon a stationary table 52 which is located at the rear of the compressor. To control the closing movement of the fingers, screws 54 are provided which are 30 threaded through the members 42 and are adjusted to engage the outer ends of the fingers after a predetermined closing movement of the fingers has been effected by movement of the links 46 away from the 35 compressor. The screws 54 may be so set that when the ends 47 of the fingers engage the sides of the heel being treated the screws will limit further movement of the fingers and prevent lateral displacement of the 40 heel by movement of one finger farther than the other. This construction minimizes mispositioning of the heel due to springing or lost motion of the parts, and if the heel is in such position that one finger engages it 45 first that finger will shift the heel and position it properly in engagement with the other finger.

At their rear ends the links 46 are pivot- 45 ed at 58 in the slotted ends of a short cylin- drical member 60 which is mounted to turn

in the lower end of an arm 62 and is held from longitudinal movement by a screw 64 engaging a groove formed in the member 60. At its upper end the arm 62 (Fig. 1) is integrally connected with a sleeve member 63 70 which is rotatably mounted on a shaft 65 journaled in a frame 66 bolted to the main frame 1. On the sleeve member 63 is another arm 68 slotted at 70 to receive a block 72 (Fig. 2) which is adjustable lengthwise 75 of the slot by means of a tongue 74 attached to the block and rotatably connected to an adjusting screw 76 threaded into the end of the arm 68. An eye-bolt 78 passes freely through the block 72 and is secured by a nut 80 80. A rod 82 (Fig. 1) extends through the eye of the bolt 78 and at its lower end is pivotally connected at 84 with the vertically movable head 2 of the compressor. A spring 86 is arranged on the rod 82 between the eyebolt 78 and a stop nut 87 on the rod 82 and above the eye-bolt 78 is a stop nut 88. A stop screw 90 is threaded through a lug 92 on the frame 66 in position to engage a stop projection 91 on the sleeve member 63 and 90 limit upward movement of the arm 68 and inward movement of the arm 62.

The operation of the fingers 36 will now be understood by reference particularly to Fig. 1. It will be seen that as the head 2 95 moves upwardly the rod 82 will push through the spring 86 upon the eye-bolt 78 connected to the arm 68 and will rock the sleeve member 63, causing the arm 62 to move the links 46 to open the fingers and move them inwardly of the machine until the lugs 50 are located beyond the breast face of the heel. This inner position is determined by the stop screw 90 which limits movement of the arm 62 by engaging the lug 91, the screw, of course, being readily adjustable to vary the inner position of the fingers. Further upward movement of the head 2 is permitted by compression of the spring 86. During downward movement of the head 2 no movement of the finger takes place until the head is near the lower limit of its movement and the ejector has removed a heel from the mold. During the first part 100 of the downward movement of the head the compression of the spring 86 is released, and finally the space between the stop nut 88 and the eye-bolt 78 is taken up, allowing the nut 88 to engage the eye-bolt 78 and effect a movement of the arm 68 and arm 62 positively to withdraw the heel from the machine and to present it in a predetermined position upon the table 52. The head 2, of course, always returns to the same position and by adjusting the screw 76 the effective 110 length of the arm 68 may be varied to cause the heel to be presented on the table in predetermined but variable positions longitudinally of the heel.

The table 52 has a central hub 98 (Fig. 3) 130

which is rigidly clamped in a boss 100 formed on a supplemental frame 102 bolted to the main frame 1 as shown. Arranged centrally of the hub 98 is a short shaft 104 on the upper end of which (Fig. 7) is secured a spider 106. Pivoted to the spider at 108 are four pairs of jaws 110 which constitute with the spider an endless carrier for the heels. The spider 106 is moved intermittently by mechanism to be described to present each pair of jaws in turn and permit them to dwell at successive stations A, B, C and D. The jaws of each pair are connected together for equal and opposite movement by interengaging teeth 112 and their closed position is adjustably determined by a screw 114 having a threaded mounting on the spider and engaging a pin on one of the jaws. The jaws are held toward each other by springs 116. It will be noted from Fig. 3 that each of the jaws is double, comprising a lower downwardly bent portion 111 which engages the surface of the table 52 and the portion 110 which is attached by screws to the lower jaw 111 and extends upwardly at a slight angle. The end portions 47 of the fingers 36, as they are moved to force the heel on to the table between the pair of jaws located at station A, pass between the lower and upper portions of the jaws, the jaws separating if necessary against the spring 116 to permit the entrance of the heel to the heel engaging surfaces of the jaws and being preferably serrated or toothed securely to hold the heel in the position in which it is presented.

It has been found preferable to have the jaws open at the time the heel is presented between them since when the jaws are yieldingly held together during insertion of the heel there is apt to be unequal resistance offered by the jaws with a consequent shifting of the heel in the plane of its toplift from the position determined by the transferring fingers 36. Therefore, it is preferable to provide adjacent to station A means to engage a projection 206 on one of the fingers and cause the fingers to be opened while they are at rest at station A. This means comprises a cam member 51 (Figs. 6, 7 and 12) which is adjustably fixed to the mold slide by screws 55. The member has a downwardly and inwardly inclined face 53 which engages the projection 206 during the downward movement of the mold slide and causes the jaws to open prior to the insertion of the heel between them. Further movement of the slide carries the cam face 53 beyond the projection, allowing the jaws to close upon the heel. The jaws then start to move toward station B and the projection is out of the way of the cam 51 during the next upward movement of the mold slide.

The amount removed from the heel in the 65 breasting operation will depend upon its

longitudinal position in the jaws and it is consequently desirable to provide a gage or stop for limiting the longitudinal movement of the heel. As shown, a plate 120 is provided beneath each pair of jaws, the plate 70 having a V-shaped portion to engage the rear end of the heel. Each plate is arranged to slide longitudinally of the heel and is held in adjusted position by a screw 122 engaging a slot in the spider 106 and threaded into 75 the plate 120.

Since each of the gage plates 120 should be set at the same distance from the center of the spider shaft 104, it is desirable to provide means for adjusting the plates 80 simultaneously and for locating them at equal distances from said center. As shown, a cam plate 113 is arranged beneath the spider for rotation relatively to the spider about the spider shaft 104. The cam plate 113 has 85 four slots 119 extending from its edge inwardly at an angle and each slot is engaged by a pin 119^x on the corresponding gage plate 120. By loosening the screws 122 and turning the cam 113 the gage plates 120 may 90 be moved equally and simultaneously in either direction lengthwise of the jaws 110. For conveniently turning the cam 113 a pin 115 fixed thereto extends up through a slot 117 in the spider 106, the slot being curved 95 concentrically with the shaft 104 and the pin 115 being used as a handle for turning the cam. By moving the cam 113 to its limit in one direction the open ends of the slots 119 will release the pins 119^x and permit the plates 120 to be removed and others adapted 100 for a different range of heel sizes to be substituted therefor.

Adjacent to the lower end of the spider shaft 104 is mounted, in the frame 102 and in 105 a bracket 121, a shaft 123 having at its lower end a gear 124 meshing with a pinion 126 on a shaft 128 which is mounted in the frame 102. On the shaft 128 is a gear 130 meshing with a gear 132 on the shaft 9. The shaft 104 is connected to the shaft 123 by intermittent gearing which may be of any suitable kind and is shown (Fig. 8) as of the Geneva type, the construction being such that a single rotation of the shaft 123 will 115 cause a member 134 fixed to the shaft to impart a quarter revolution to a member 136 fixed to the shaft 104, it being understood that the movement imparted to the shaft 104 will take place during a relatively small 120 part, for example 90°, of the rotation of the shaft 123 and that during the rest of the rotation the member 136 will be locked from rotation and held in predetermined position with one pair of jaws 110 at the station A 125 (Fig. 7) and another pair at the station B of that figure. The rotation ratio of the gear 132 to the gear 130 is 1 to 2 and the rotation ratio of the pinion 126 to the gear 124 is 2 to 1, and the relative timing of the gearing 130

is such that the jaws will be at rest while the heel is being removed from the compressor by the fingers 36 and after the heel is inserted in the jaws the spider 106 and 5 jaws will be rotated to bring the jaws and the heel held in them to the station B where the jaws will remain at rest for a sufficient time to permit the breasting operation to be performed.

10 The breasting mechanism is mounted on an upward extension 140 (Fig. 3) of the frame 102 and comprises a knife slide 142 mounted for vertical reciprocation in the frame. An adjustable connecting rod 144 15 is pivoted to the knife slide at 146 and is carried at its lower end by a crank pin 148 on a crank 150 secured to the shaft 128 so that a vertical reciprocation will be imparted to the knife slide as the shaft 128 20 rotates. A knife 152 (Fig. 5) is clamped in the knife slide by a screw 154 and is adjustably held vertically by an abutment screw 156. When the slide descends the knife operates to remove material from the 25 breast end of the heel and is arranged to co-operate with the edge of the table upon which the heel rests to effect a shear cut upon the heel. As shown the dwell at station B covers one and a half rotations of 30 the shaft 128 and hence the knife makes two strokes across the heel while the heel is at rest, the movement of the carrier occurring in the interval between the time when the knife leaves a heel on its second 35 up stroke and the time when the knife reaches another heel on its next down stroke.

In order that knives of different curves may be used for breasting the heels and may co-operate with the table to effect a 40 shear cut without changing the table, the portion of the table upon which the heel rests is made detachable as shown in Fig. 7. The table is provided with ledges 158, 158 upon which a block 160 rests with its upper 45 surface flush with the surface of the table. The front edge of the block 160 is contoured to correspond with the curve of the knife and a screw 162 is threaded through a lug on the table in position to engage the inner 50 end of the block 160 to limit its inward movement and to provide means for adjusting the block so that its front edge will properly co-operate with the knife. The block preferably has tongues 161 on its 55 sides which engage grooves in the table and the block 160 is held in the table by buttons 164 held to the table by screws 166 and arranged to engage the tongues 161 of the block 160. When the screws 166 are 60 loosened the buttons 164 may be turned up against pins 165 (Fig. 7) to permit removal of the block 160. To take the thrust of the knife against the block 160 an abutment screw 167 (Fig. 3) is threaded into 65 the frame 102 beneath the block 160 and

may be adjusted vertically so that its head will bear against the lower face of the block and support it.

While the heel is being moved from its position over the mold to its position on the 70 table the mold is moving downwardly and the plane of the top face of the mold is in the plane of the table only when the mold is at the lower limit of its movement.

Therefore, at the time when the heel passes 75 from the mold on to the table the mold is

somewhat above the table and a downward tilting of the heel occurs as it passes from the mold to the table. If the jaws are not 80 opened to receive the heel when the heel is pushed into them they may not allow the lower face of the heel to come in firm contact with the table. Hence it is desirable to provide means to press the heel firmly 85 down upon the table at the station A. If

the jaws are open at this time, as proposed above, it is desirable to provide means to hold the heel pressed down against the table

in the position given to it by the fingers

90 36 when the jaws close upon the heel. Accordingly a pressure 168 is arranged for vertical reciprocation in the frame 66 in position to engage the heel with its lower out-

wardly bent end 169 and to press the heel firmly in contact with the table. Fixed at 95

one end of the presser 168 is a laterally extending arm 171 having at its other end

a sleeve 173 arranged to slide on an operat-

ing rod 175 which is pivoted to the head

2 by the pin 84. On the rod 175 between 100

the sleeve 173 and an adjusting nut 177 is

a stiff spring 179 and on the rod 175 be-

tween the sleeve 173 and a fixed collar 181

is a weaker spring 183. Extending upward-

ly as a continuation of the presser 168 is a 105

rod 185 guided in the frame 66 and having

an adjustable stop collar 187 which engages

the frame 66 to limit upward movement of

the presser. As the head 2 moves upward-

ly the spring 183 acts upon the arm 171 to 110

lift the presser 168 as far as permitted by

the collar 187, and during downward move-

ment of the head 2 the presser is moved

into contact with the heel and pressure ap-

plied thereto through the stiff spring 179. 115

The timing is such that the presser is lifted

during the passage of the heel from station

A to station B.

It is desirable to clamp the heel against

the table during the action of the knife and

for this purpose a clamp 170 is provided

which has a downwardly bent end adapted

to engage the heel near the knife. The

clamp 170 is fixed to the lower end of a

rod 172 which is guided through a boss 174

on the frame 140 and at its upper end has

a frictional connection 176 with a bracket

178 secured to the knife slide 142. During

the downward movement of the knife the

clamp 170 is brought into contact with the

heel before the knife engages it and the friction means 176 then slips on the rod 172 during the cutting operation of the knife, the clamp being restored to its original position upon upward movement of the slide 142.

It may sometimes happen that a blank or heel is not positioned on the support 160 in proper position for a subsequent operation, for instance a heel for breasting, but is displaced slightly longitudinally or rotationally or both. Accordingly relatively power operated positioning members comprising the gage plate 120 and a member 180 are provided which act on the blank and cooperate to determine both its longitudinal position and its rotational position or orientation, that is, the direction of its longitudinal median line. As herein shown means is provided for insuring that the breast face of the heel will be positioned in proper relation to the breasting knife for the breasting operation. Usually this position will be with the breast face of the heel parallel to the edge of the knife. For this purpose the member 180 hereinafter called a striker is provided which is brought against the breast end of the heel just prior to the breasting operation. Preferably the portion of the striker which engages the heel corresponds in shape to that of the compressed breast face of the heel and is arranged vertically so that it will strike the toplift portion only of the heel which portion has usually the more uniform shape in a compressed heel. It is essential only, however, that the striker engage the edge face of the blank or heel at points separated a substantial distance laterally of the blank or heel. If the heel in the jaws is improperly positioned the contact of the striker 180 with the lower or toplift portion of the breast face will cause the heel to move rotationally in a horizontal plane until its breast face is in the same direction as the striking face of the striker, and longitudinally until it is against the gage plate 120, if it does not already engage it, the result being that the heel will then be positioned longitudinally so that it will be breasted to the proper length and will have its breast face in proper relation to the knife for the breasting operation. This proper relation is usually, in treating heels of the broad, low type shown, such that the breast face of the heel is parallel to the plane of action of the knife, that is, with its longitudinal median line substantially perpendicular to the plane of the knife. The striker 180 is mounted on the lower end of a lever 182 having its upper end bent and pivoted at 184 to the frame 140. Below the pivot 184 a spring 186 is provided between the lever 182 and the frame 140 to move the striker toward the heel. A lock-

ing mechanism (Fig. 4) is provided for holding the striker normally away from the heel and comprises a link 188 pivoted to the frame 140 at 190 and having at its other end a notch adapted to engage a pin 192 on the lever 182 and hold the striker away from the heel in the position shown. A link 194 is pivoted at 196 to the frame 140 at one end and at its other end is connected by a link 198 to the link 188. The pivots 190, 196 are preferably provided with friction means to cause the links 188, 194 to remain in any position to which they are moved. These friction means may comprise lock washers 197 placed between the links 188, 194 and the frame 140 on the pivot screws 190, 196 (Fig. 10). A detail of one of the washers 197 is shown in Fig. 11. The washer is split and the ends bent somewhat out of line, one end being provided with a sharp lip 199 which digs into the part engaged by it and causes the washer to move frictionally against the part engaging its opposite side. The washer will yield somewhat to pressure of the screw which may be adjusted to secure the proper amount of friction. A roll 200 is arranged on the knife slide 142 in position to engage the link 194 when the slide is nearly in its uppermost position, the roll acting to lift the link 194, and, through the link 198, also the link 188 to release the end of that link from the pin 192 and permit movement of the striker toward the heel. This movement, however, is controlled by two cams 202, 204 fixed to the lever 182 and having edges which engage the roll 200. As the carrier and roll 200 move downwardly the roll will pass off the lower end of the cam 202 before the knife reaches the heel and allow the striker 180 to be actuated by the spring 186 against the heel to position it for the action of the knife. As the movement of the roll continues downwardly it engages the cam 204 and pushes the lever 182 outwardly sufficiently to allow the link 188 to come again into locking engagement with the pin 192, then the roll 200 engages the link 188 and moves it against the friction holding means into locking position, the parts remaining in this position until the return movement of the roll 200 has been nearly completed.

As has been described, the knife makes two strokes while the heel is in the same position. The first cut removes material from the breast end of the heel by what may be called a roughing cut. The second passage of the knife across the breast face of the heel smooths up the breast face and is referred to as a finishing cut.

Upon the next intermittent partial rotation of the spider 106 the heel will be carried to station C and a new heel brought into station B for the breasting operation. Upon

the next partial rotation of the spider 106 the first heel treated will be brought to station D and as it approaches this position a projection 206 on one of the jaws 111 will engage a jaw releasing member 208 adjustably fixed to the table 52 and adapted to be engaged by the projection 206 temporarily to arrest movement of that jaw. By reason of the inter-connection 112 between the jaws, 5 the opposite jaw will be correspondingly opened and the heel allowed to drop through an opening in the table at the station D where suitable means may be provided to receive the heels. Upon the next movement of 10 the spider 106 the projection 206 will ride off the member 208 and allow the jaws to be closed by their spring 116 before they reach station A again.

It is desirable so to mount the member 208 20 that it will yield after sufficient pressure has been applied to the projection 206 to open the jaws and also to provide means to enable the projection to pass the member 208 without obstruction if the spider is turned backwardly, as is sometimes necessary, as for instance, when an abnormally thick heel is presented to the compressor and the machine "sticks" and fails to "go over." It is then necessary to throw off the power and turn 25 the machine backwardly by hand to enable the heel to be removed. Since the spider 106 is geared to the compressor, the spider also must be turned backwardly and the jaw projection 206 will engage the member 208, 30 and either that or the jaw be bent or broken if the member is not arranged to permit free rearward movement of the projection 206 past it. The member 208 is, therefore, pivoted to turn a partial rotation on a pin 210 35 carried by a block 212 which rests on a ledge 214 formed on a supporting member 216 which is adjustably secured to the lower face of the table by screws 220. The screws pass through slots in the member 216 which are 40 arranged in the general direction of the edge of the table so that the member 216 may be set in various positions along the edge of the table to vary the point in the rotation of the spider at which the jaws will be 45 opened. The block 212 has a stem 222 about 50 which is a spring 224 arranged to hold the block 212 inwardly against the supporting member 216 and permit it to yield outwardly so that the projection 206 can pass the member 208 after the jaws are opened. The member 208 has a downward projection 226 which 55 engages a face on the block 212 to limit its turning movement in a counter-clockwise direction and the member is normally held at 60 this limit by a spring 228 connected between the member 208 and the supporting member 216. If the spider 106 is turned backwardly 65 the projection 206 of the jaw will strike a face 230 on the member 208 and the member will turn on its pin 210 against the tension

of the spring 228 and allow the projection 206 to pass without bending or breaking the jaw.

Having thus described my invention, what I claim as new and desire to secure by Letters Patent of the United States is:

1. In a machine for compressing and breasting heels in a continuous operation, means for compressing a heel, means for feeding the heel to the compressing means, 75 means for ejecting the heel from the compressing means, means independent of the feeding means for transferring the heel from ejected position to breasting position, and means for breasting the heel while in 80 said position.

2. In a machine of the class described, the combination of vertically movable heel compressing means, heel breasting means, 85 and means associated with the compressing means and operating to take a heel from the compressing means at the conclusion of the compressing operation and transfer it by horizontal movement to the heel breasting means.

3. In a machine of the class described, the combination of relatively movable heel compressing means, means movable relatively to the heel compressing means for delivering a compressed heel from the heel compressing means, heel breasting means, and mechanism for transferring the heel from said delivering means to the heel breasting means with the direction of the height of the heel unchanged.

4. In an organized machine, the combination of vertically movable means, means movable relatively to said means for presenting a heel in predetermined relation above said vertically movable means, fingers guided on said vertically movable means for movement therewith and also movable horizontally, means for operating the fingers to grasp the heel in the position in which it is presented and to carry the heel to another position, means for transferring the heel from said other position to a third position, and means for operating upon the heel while in the third position.

5. In an organized machine, the combination with heel compressing molds and means for ejecting a heel from the molds after compression of the heel, of a carrier constructed and arranged for movement in a horizontal plane, means for taking the heel from ejected position and presenting it in position in said carrier, and means for performing another operation upon the heel while in transit in said carrier.

6. In an organized machine, the combination with heel compressing molds and an ejector which presents a heel after compression in predetermined position above the molds, of an endless carrier, means guided by the molds and movable therewith for 125

- taking the heel from ejected position and presenting it in predetermined position in the carrier, and means for operating upon the heel while in transit in said carrier.
5. 7. In an organized power driven machine for compressing and breasting heels automatically in a continuous operation, the combination with means for compressing and delivering a heel in predetermined position, of heel breasting means, and means for transferring the heel substantially in a horizontal plane from the compressing means and presenting it to the breasting means.
10. 8. In an organized power driven machine for compressing and breasting heels automatically in a continuous operation, the combination with means for compressing and delivering each heel in a predetermined position, of means for transferring each heel to a second predetermined position, a plurality of means operating intermittently and successively to take the heels in turn and present each heel in another position, and means for breasting each heel while in 25 that last-named position.
15. 9. In an organized power driven machine for compressing and breasting heels automatically in a continuous operation, the combination with means for compressing and delivering a heel in predetermined position, of reciprocating means for transferring the heel to a second predetermined position, irreversible rotary means for transferring the heel from said second position 30 to a third position, and means for breasting the heel while in said third position.
35. 10. In an organized machine, the combination of movable means, means movable relatively to said means for presenting a heel in predetermined relation above said movable means, fingers guided on said movable means for movement therewith and also transversely of said movement, means for operating the fingers to grasp the heel in 40 the position in which it is presented and to carry the heel to another predetermined position, means for transferring the heel from said predetermined position to another position, and means for there operating upon 45 the heel.
50. 11. In an organized machine, the combination with heel compressing molds and an ejector which presents a heel after compression in predetermined position above the molds, of a table, means for taking the heel from ejected position and presenting it in predetermined position upon the table, a carrier movable over the table to transfer the heel to another predetermined position, and means for operating on the heel while in 55 said position.
60. 12. In an organized machine, the combination with heel compressing molds and an ejector which presents a heel after compression in predetermined position above 65 the molds, of a table, heel transferring means guided by the molds and movable therewith for taking the heel from ejected position and presenting it in predetermined position upon the table, and means on the table movable transversely to the path of heel presenting movement for transferring the heel to another position.
70. 13. In an organized power driven machine for compressing and breasting heels automatically in a continuous operation, the combination with means for compressing and delivering a heel in predetermined position, of positively acting means for transferring the heel to a second predetermined position, relatively movable jaws to receive the heel in said second position, rotary means for moving the jaws bodily to transfer the heel from said second position to a third position, and breasting means constructed and arranged to operate twice upon the heel while in said third position.
75. 14. In an organized power driven machine for compressing and breasting heels automatically in a continuous operation, the combination with means for compressing and delivering a heel in predetermined position, of means at the rear of the machine for transferring the heel to a second predetermined position, means for transferring the heel from said second position to a third position, and means for breasting the heel while in said third position.
80. 15. In an organized power driven machine for compressing and breasting heels automatically in a continuous operation, the combination with means for compressing and delivering a heel in predetermined position, of fingers arranged to engage the breast face and sides of the heel, means for 85 positively moving the fingers to transfer the heel to a second predetermined position, jaws arranged to receive the heel from the fingers, means for moving the jaws bodily to transfer the heel from said second position to a third position, and means for breasting the heel while in said third position.
90. 16. In a heel breasting machine, the combination of heel supporting means, heel holding means, heel breasting means, and means having an operative movement prior to action of the breasting means upon the heel for positioning the heel in the holding means to insure that the heel will be evenly 95 breasted.
100. 17. In a heel breasting machine, the combination of heel supporting means, heel holding means, a reciprocating breasting knife, and means caused to operate by the breasting knife during its breasting stroke to engage and position the heel with its breast face substantially parallel with the knife edge.
105. 18. In a heel breasting machine, the com- 120

bination of heel supporting means, heel holding means, heel breasting means, and means, operated during movement of the breasting means and prior to its contact with the heel, to engage the breast face of the toplift and position the heel in the holding means to insure that the heel will be evenly breasted.

19. In a heel breasting machine, the combination of heel supporting means, heel holding means, a reciprocating breasting knife, and spring actuated means normally withheld from the heel and controlled by the breasting knife to cause it to engage the breast of the heel and position the heel with its breast face substantially parallel with the knife edge.

20. In a machine of the class described, the combination of a reciprocating breasting knife, means for positioning the heel prior to the action of the knife, and frictionally held means operated by movement of the knife for preventing operation of the positioning means during the inactive stroke of the knife.

21. In a heel breasting machine, the combination of heel supporting means, heel holding means, a reciprocating breasting knife, a knife carrier, a striker, a support for the striker, a spring for actuating the striker toward the heel breast, and means between the knife carrier and the striker support for causing the striker to act during the breasting stroke of the knife.

22. In a heel breasting machine, the combination of heel supporting means, heel holding means, a reciprocating breasting knife, a knife carrier, a striker, a support for the striker, a spring for actuating the striker toward the heel breast, a roll on the knife carrier, and cams on the striker support with which the roll co-operates to permit the striker to engage the heel prior to engagement of the heel by the knife and then to retract the striker.

23. A heel breasting machine having, in combination, heel supporting means, heel holding means, a reciprocating breasting knife, a knife carrier, a striker, a support for the striker, a spring for actuating the striker toward the heel breast, means for locking the striker in retracted position, means for releasing the locking means when the knife is raised, and means for controlling the action of the striker for permitting it to act upon the heel and for again locking the striker in retracted position while the knife ascends.

24. In a heel breasting machine, the combination of heel supporting means, heel holding means, a reciprocating breasting knife, a knife carrier, a roll on the carrier, a striker, a support for the striker, a spring for actuating the striker toward the heel breast, and cams on the striker support co-operat-

ing with the roll to permit action of the spring during the breasting stroke to cause the striker to engage and straighten the heel and then to re-tension the spring prior to the breasting action of the knife.

70

25. In a heel breasting machine, the combination of heel supporting means, heel holding means, a reciprocating breasting knife, means controlled by the breasting knife during its breasting stroke to position the heel with its breast face substantially parallel to the knife, and means for holding the positioning means in inoperative position during the return stroke of the knife.

75

26. In a machine of the class described, the combination of a table, a pair of interconnected jaws movable over the table, and means on the table in the path of one of the jaws to effect relative separation of the jaws during movement of the jaws and constructed and arranged to permit closing of the jaws as movement of the jaws continues.

85

27. In a machine of the class described, the combination of a table, pairs of interconnected jaws movable over the table, means for holding the jaws normally closed, means for effecting bodily movement of the jaws intermittently, and means on the table in the path of one of the jaws to effect relative separation of the jaws during bodily movement of the jaws and constructed and arranged to permit closing of the jaws as movement of the jaws continues.

90

28. In a machine of the class described, the combination of a fixed table, heel holding means arranged for intermittent movement over the table, means for operating upon a heel during a dwell of the holding means, and a stop on the table in the path of the holding means and acting upon movement thereof subsequent to the operation upon the heel to effect release of the holding means.

100

29. In a machine of the class described, the combination of a fixed table, jaws arranged for movement over the table, and a yielding stop on the table in the path of one of the jaws to arrest that jaw and cause the jaws to open.

105

30. In a machine of the class described, the combination of a fixed table, jaws on the table arranged for movement over the table, and means on the table in the path of one of the jaws comprising a yielding element arranged to cause arrestment of one of the jaws to effect opening of the jaws and adapted to yield to permit passage of the jaws after the jaw is opened.

115

31. In an organized power driven machine for compressing and breasting heels automatically in a continuous operation, the combination with means for compressing and delivering a heel in predetermined position, of means for transferring the heel to a second predetermined position, jaws to re-

120

125

130

- ceive the heel, means operating intermittently to move the jaws bodily to locate the heel in another position, means for breasting the heel while in that position, and means operated by movement of the jaws bodily to effect relative movement of the jaws for releasing the heel at a point remote from the breasting position.
32. In a machine of the class described, the combination of a stationary table, a carrier comprising relatively movable jaws arranged on the table, means for presenting a heel in the jaws, means for giving the carrier successive partial rotations, means for treating the heel while the heel is at rest after one of said partial rotations, and means on the table arranged to engage one of the jaws to effect release of the heel and allow the heel to fall from the jaws.
33. In a machine of the class described, the combination of a stationary table, a carrier having jaws connected for equal and opposite movement, yielding means for holding the jaws normally closed, means for effecting intermittent movements of the jaws over the table, means for presenting a heel between the jaws to be held thereby while the jaws are at rest in one position, means for breasting the heel while the jaws are at rest in another position, and means acting during movement of the jaws after the breasting operation to separate the jaws and allow discharge of the heel from the jaws.
34. In a machine of the class described, the combination of a fixed table having an opening, heel holding means on the table arranged for movement across the opening, and means on the table in the path of the holding means to cause the holding means to release the heel as the heel passes over the opening.
35. In a machine of the class described, the combination of a fixed table having an opening, jaws on the table arranged for movement across the opening, and means on the table in the path of one of the jaws comprising a yielding element arranged to cause arrestment of one of the jaws to effect opening of the jaws and adapted to yield to avoid putting excessive strain on the jaws.
36. In a machine of the class described, the combination of a stationary table having an opening, a carrier comprising a series of pairs of relatively movable jaws arranged for movement over the table, means for presenting a heel to each pair of jaws, means for giving the carrier intermittent movements, means for breasting each heel while the heel is at rest after one of said movements, and means on the table arranged to engage one of the jaws of each pair in succession to effect release of the heel and allow the heel to fall through the opening in the table.
37. In a machine of the class described, the combination of a table, a pair of jaws movable over the table, and a lug in the path of one of the jaws arranged to arrest movement of the jaw when the jaw engages it on one side and arranged to turn to permit passage of that jaw past the lug when the jaw is moved backward to engage the lug on the opposite side.
38. In a machine of the class described, the combination of a table, a pair of interconnected jaws movable over the table, and means on the table in the path of one of the jaws to effect relative separation of the jaws during movement of the jaws and constructed and arranged to permit closing of the jaws as movement of the jaws continues, said means being constructed and arranged to permit unobstructed reverse movement of the jaws relatively to the table.
39. In a machine of the class described, the combination of a table, pairs of interconnected jaws movable over the table, and a jaw opener on the table in the path of one of the jaws to effect relative separation of the jaws during movement of the jaws and constructed and arranged to permit closing of the jaws as movement of the jaws continues, said opener being arranged for pivotal movement to permit reverse movement of the jaws relatively to the table.
40. In a machine of the class described, the combination of a table for supporting unattached heels, means for advancing the heels step by step over the table, and a reciprocating knife acting in the direction of the height of a heel while the heel is at rest constructed and arranged so that the knife acts past the edge of the table and the table co-operates with the knife to effect a shear cut upon the heel.
41. In a machine of the class described, the combination of a reciprocating knife, a table for supporting a heel, means for transferring heels on the table into operative relation to the knife, and a block inserted in the table with its top face flush with the top of the table and having one edge parallel with the knife, said edge being arranged to co-operate with the knife to effect a shear cut when the knife acts upon the heel.
42. In a machine of the class described, the combination of a reciprocating knife, a table for supporting a heel, means for transferring heels from the table into operative relation to the knife, a block inserted in the table with its top face flush with the top of the table and having one edge face parallel with the knife, and means for adjusting said face toward the knife so that it will co-operate with the knife in making a shear cut when the knife acts upon the heel.
43. In a machine of the class described, the combination of a reciprocating knife, a table for supporting a heel and a block guided in the table for movement substan-

- tially perpendicular to the knife, a screw back of the block for adjusting the block toward the knife, and means for holding the block in the table against the screw.
- 5 44. In a machine of the class described, the combination of a knife carrier adapted to hold knives of different curvature, and a support adapted to receive and hold interchangeable blocks each having a face corresponding to one of the knives, each block being adapted to support a heel and to cooperate with its respective knife to effect a shear cut upon the heel, the heel being presented with one of its relatively flat faces 10 in contact with the block.
45. In an organized power driven machine for compressing and breasting heels automatically in a continuous operation, the combination with means for compressing 20 and delivering a heel in predetermined position, of heel breasting means, and means for transferring the heel from said delivering position and presenting it to the heel breasting means, said heel breasting means 25 being constructed and arranged to operate twice upon the heel.
46. In a heel breasting machine, means for presenting an unattached heel in position to be breasted, breasting means, and means for operating the breasting means twice while the heel remains in the same position.
47. In a heel breasting machine, means for presenting a heel to be breasted, breasting means, means for operating the breasting means twice while the heel remains in the same position, and means for moving the heel away from breasting position.
48. In a heel breasting machine, means for presenting a heel to be breasted, breasting means, means for operating the breasting means twice while the heel remains in the same position, means for moving the heel away from the breasting position, and means for releasing the heel.
49. In a heel breasting machine, a series of movable jaws for presenting heels to be breasted, means for moving the jaws intermittently, breasting means, and means for operating the breasting means twice during a single dwell of the jaws.
50. In a machine of the class described, the combination of a stationary table, a carrier having jaws, means for effecting intermittent movements of the jaws over the table, means for presenting a heel in the jaws while the jaws are at rest in one position, and means for breasting the heel after the jaws are moved to another position.
51. In a machine of the class described, the combination of a pair of jaws, means for holding the jaws yieldingly closed, means for transferring a heel in the plane of the jaws and lengthwise of the jaws from a remote position into position between the jaws, and means operating in time relation 60 to the transferring means for opening the jaws to allow free passage of the heel between them and then allowing the jaws to close.
52. In a machine of the class described, the combination of a pair of jaws, means for holding the jaws yieldingly closed, vertically movable means, means operated by said vertically movable means for opening the jaws to allow free passage of the heel between the jaws and then permitting the jaws to close upon the heel, and means for transferring a heel from the vertically movable means to a position between the jaws while they are open.
53. In a machine of the class described, the combination of a series of pairs of yieldingly closed jaws, means for moving the series intermittently to locate each pair at various stations successively, means for opening each pair of jaws while at rest at one station, means for opening each pair of jaws during its movement of approach to another station, and means for performing an operation upon the heel between said stations.
54. In a machine of the class described, the combination of a pair of jaws connected for equal and opposite movement, one of said jaws having a lateral projection, means for holding the jaws yieldingly closed, vertically movable means, means for transferring a heel from the vertically movable means to a position between the jaws, and means operated by said vertically movable means for opening the jaws to allow free passage of the heel between the jaws and then permitting the jaws to close upon the heel.
55. In a machine of the class described, the combination of a series of pairs of yieldingly closed jaws, means for moving the series intermittently to locate each pair at various stations successively, means for opening each pair of jaws while at rest at one station, and means for opening each pair of jaws during its movement of approach to another station.
56. In a machine of the class described, the combination of a series of pairs of yieldingly closed jaws, means for moving the series intermittently to locate each pair of jaws at various stations successively, means for opening each pair of jaws while at rest at one station, means for feeding a heel to each pair of jaws while open and at rest, means for opening each pair of jaws during its movement of approach to another station, and means for breasting the heel held by the jaws at a station between the stations where the jaws are opened.
57. In a machine of the class described, the combination of vertically movable means carrying a heel, stationary means, a plurality of pairs of jaws movable over 130

- 5 said means, means for transferring a heel from the vertically movable means while in motion to a pair of jaws on said stationary means, means operated by said vertical movement for causing the jaws to open to receive the heel and then to close, means for pressing the heel against said stationary means while the jaws are closing and then releasing the heel, and means for moving the 10 jaws over said stationary means to another position.
58. In a machine of the class described, the combination of a reciprocating breasting knife, heel positioning means acting to engage the heel breast prior to action of the knife, cams for controlling the positioning means, and a frictionally held lock operated by the knife movement to prevent operation of the positioning means during the 15 idle stroke of the breasting knife.
59. In a machine of the class described, the combination of a plurality of pairs of superimposed heel holding jaws connected for equal and opposite movement, one pair 20 being arranged to engage the sides of the heel adjacent to its tread face and another pair being arranged to engage the sides of the heel adjacent to its seat face.
60. In a machine of the class described, 25 two pairs of superimposed jaws adapted to receive a heel, a pair of fingers, and means for operating the fingers to seize and transfer a heel into the jaws, the fingers being constructed and arranged to pass between the upper and lower pairs of superimposed jaws.
61. In a machine of the class described, a plurality of pairs of jaws, a back gage for each pair of jaws to limit the longitudinal 30 position of a heel in the jaws, and means for adjusting the gages in unison to vary the longitudinal positions of the heels in the jaws.
62. In a machine of the class described, 35 a plurality of pairs of jaws, a back gage for each pair of jaws to limit the longitudinal position of a heel in the jaws, and means for adjusting the gages equally and simultaneously to vary the longitudinal positions of the heels in the jaws.
63. In a machine of the class described, 40 a plurality of pairs of jaws, a back gage for each pair of jaws to limit the longitudinal position of a heel in the jaws, and means for adjusting the gages in unison, said means being arranged to release the gages to permit their removal when in one position of adjustment.
64. In a machine for compressing and 45 breasting heels in a continuous operation, means for compressing a heel, means for feeding the heel to the compressing means, means for ejecting the heel from the compressing means, means for transferring the heel from ejected position to breasting position while maintaining the plane of the tread face of the heel unchanged, and means for breasting the heel while in breasting position.
65. In a machine for compressing and 50 breasting heels in a continuous operation, means for compressing a heel, means for feeding the heel to the compressing means, means for ejecting the heel from the compressing means, means independent of the feeding means for transferring the heel from ejected position, and means acting to breast the heel while the heel is in transit on the transferring means.
66. In a machine for compressing and 55 breasting heels in a continuous operation, means for compressing a heel, means for feeding the heel to the compressing means, means for ejecting the heel from the compressing means, means including movable fingers for transferring the heel from ejected position to breasting position, means for operating the fingers to seize and transfer the heel, and means for breasting the heel after 60 transference.
67. In a machine for compressing and 65 breasting heels in a continuous operation, means for compressing a heel, means for feeding the heel to the compressing means, means for ejecting the heel from the compressing means, fingers for transferring the heel from ejected position to another position, means for operating the fingers to cause them to open while passing the heel, then 70 to close behind the heel and against its sides and then to carry it to said other position, means for conveying the heel to a third position, and means for breasting the heel while in said third position.
68. In a machine for compressing and 75 breasting heels in a continuous operation, vertically movable means for compressing a heel, means for feeding the heel to the compressing means, means for ejecting the heel from the compressing means, and means independent of the feeding means operated by 80 said vertically movable means for transferring the heel positively from ejected position to another predetermined position.
69. In a machine of the class described, 85 relatively movable compressing molds, an ejector for presenting a heel after compression above the molds, slides mounted one on each side of the ejector for movement longitudinally of the heel, finger levers pivoted to the slides, and connections to the levers operating when moved in one direction to open the fingers and move them past the heel and when moved in the other direction to close the fingers upon the heel and 90 transfer the heel.
70. In a machine of the class described, 95 means for compressing a heel, means for feeding a heel to the compressing means, means for ejecting the heel from the com- 100

- pressing means, heel transferring means movable longitudinally of the heel independently of the feeding means and transversely of the heel, and operating means 5 to cause the transferring means to move past the heel longitudinally, to move laterally to engage the heel, and then to move longitudinally in the opposite direction to transfer the heel.
- 10 71. In a machine of the class described, means for compressing a heel, means for feeding the heel to the compressing means, means for ejecting the heel from the compressing means, heel transferring means movable longitudinally of the heel independently of the feeding means and transversely of the heel, and means operated by vertical movement of the compressing means to cause the transferring means first to move past the heel longitudinally thereof, then to move laterally to close upon the heel, and then to move longitudinally of the heel to transfer the heel.
- 15 72. In a machine of the class described, relatively movable compressing molds, an ejector for presenting a heel after compression above the molds, slides mounted one on each side of the ejector for movement longitudinally of the heel, finger levers pivoted to the slides between their ends, and connections to the outer ends of the levers operating when moved in one direction to separate the inner ends of the fingers and move them past the heel and when moved 30 in the other direction to close said ends upon the heel and transfer the heel.
- 20 73. In a machine of the class described, means for compressing a heel, means for feeding a heel to the compressing means, means for ejecting the heel from the compressing means, heel transferring means comprising angle levers movable bodily longitudinally of the heel and pivotally transversely of the heel, and operating means to 35 cause the angle levers to move bodily past the heel longitudinally, to move pivotally laterally to engage the heel, and then to move longitudinally in the opposite direction to transfer the heel.
- 25 74. In a machine of the class described, means for compressing a heel, means for feeding the heel to the compressing means, means for ejecting the heel from the compressing means, heel transferring fingers movable longitudinally of the heel and transversely of the heel, means to cause the transferring fingers first to move past the heel longitudinally thereof, then to move laterally to close upon the heel, and then to move longitudinally of the heel to transfer the heel, and means for independently varying the lateral closing movement of the transferring fingers.
- 30 75. In a machine of the class described, heel compressing means, an ejector for presenting a heel after compression above the compressing means, heel transferring fingers mounted for movement longitudinally of the heel to approach the heel, means for adjustably limiting movement of the fingers 70 toward the heel, and operating means for first causing the fingers to close upon the heel and then to move bodily to transfer the heel.
- 35 76. In a machine of the class described, means for compressing a heel, means for feeding the heel to the compressing means, means for ejecting the heel from the compressing means, heel transferring means movable longitudinally of the heel independently of the feeding means and transversely of the heel, operating means to cause the transferring means to move past the heel longitudinally, to move laterally to engage the heel, and then to move longitudinally in the opposite direction to transfer the heel, and means for adjusting the transferring movement of the transferring means.
- 40 77. In a machine of the class described, heel compressing means, an ejector for presenting a heel after compression above the compressing means, pivoted heel transferring fingers mounted for bodily movement longitudinally of the heel, operating means for first causing the fingers to approach the heel, to turn on their pivots to engage the heel and then to move bodily to transfer the heel, and means for adjusting the limit of movement of the operating means toward the heel.
- 45 78. In a machine of the class described, means for compressing a heel, means for feeding a heel to the compressing means, means for ejecting the heel from the compressing means, heel transferring means, operating means to cause the transferring means positively to present a heel in predetermined position, and means for adjusting the transferring movement of the transferring means.
- 50 79. In a machine of the class described, the combination of means for operating upon a heel, a fixed table, heel holding means arranged for intermittent movement in the same direction to move a heel over the table into position to be operated upon, and a stop on the table to effect release of the holding means at a later state of its movement.
- 55 80. A machine of the class described having, in combination, heel breasting means, heel compressing means, and mechanism comprising an irreversibly angularly movable carrier for transferring a heel from one of said means to the other.
- 60 81. A machine of the class described having, in combination, heel compressing means and heel breasting means organized to operate in time relation, and automatic means comprising an endless carrier for trans-

ferring the heel from one to the other of said means.

82. A machine of the class described having, in combination, means for removing surplus material from the entire breastface of a heel and for compressing the heel, and operating means to effect said treatments of the heel in succession.

83. A machine of the class described having, in combination, means for removing surplus material from a heel and for compressing the heel, operating means to effect said treatments of the heel at successive stations and transferring means to grasp the heel at one station and maintain continuous hold of the heel during transfer to the other station.

84. In a machine of the class described, the combination of vertically movable heel compressing means, means for removing surplus material from the periphery of the heel, and mechanism operatively associated with said means and acting independently thereof to take a heel from one of said means at the conclusion of its operation and transfer it by horizontal movement to the other of said means.

85. A machine for producing a compressed and breasted heel having, in combination, a heel compressing mold, a heel breasting cutter adjacent to the compressing mold and heel transferring means movable to take a heel from the compressing mold at the conclusion of the compressing operation and transfer it to the breasting cutter.

86. A machine for producing a compressed and breasted heel having, in combination, a heel compressing mold, a cutter for removing surplus material from the heel adjacent to the compressing mold, and a heel transferring device cooperatively related to the mold and cutter and movable to take a heel from the compressing mold at the conclusion of the compressing operation and transfer it with the direction of its height unchanged to the cutter.

87. In a machine for operating upon heels, the combination of vertically movable compressing molds, means for holding the heel from movement with the molds during their descent after compression of the heel, means for grasping the heel in the position in which it is left by the compressing molds as they recede from it and presenting it in position for another operation, and means for performing a further operation upon the heel so presented.

88. In a power driven machine for compressing and breasting heels automatically in a continuous operation, the combination with means for compressing a heel and for delivering the compressed heel in predetermined position over the compressing means, of heel breasting means, and means for grasping the heel in said predetermined

position, controllably transferring it and presenting it in operative relation to the breasting means.

89. In a machine for compressing and breasting heels in a continuous operation, means for compressing a heel, means for transferring the heel from compressing position to breasting position, heel breasting means, and means for positively effecting relative movement between the heel and the breasting means to cause the heel to be breasted.

90. In a machine for operating on heels, the combination of a heel compressing mold, means for presenting the heel after compression over the mold, heel breasting means adjacent to the compressing mold, and transferring means arranged to grasp the heel in the position in which it is presented over the mold and movable to transfer the heel to the breasting means, said transferring means being organized to maintain continuous control of the heel during its transference.

91. In an organized power driven machine for compressing and breasting heels, the combination with means for compressing and delivering a heel in predetermined position, of means for transferring the heel from delivered position to breasting position including irreversible means for presenting the heel in breasting position, and means for breasting the heel while so presented.

92. A machine for producing a compressed and breasted heel having, in combination, a heel compressing mold, a heel breasting knife arranged to extend in a direction substantially parallel to the breast face of the heel while in the mold, a heel transferring device cooperatively related to the mold and knife and movable to take a heel from over the mold and transfer it to a position beneath the knife, and means for relatively moving the heel and knife to cause the heel to be breasted.

93. A machine for producing a compressed and breasted heel having, in combination, a vertically movable mold carrier, a heel compressing mold on the carrier, a heel breasting cutter adjacent to the compressing mold, and a heel transferring device cooperatively related to the mold and cutter and movable horizontally to take a heel from the compressing mold at the conclusion of the compressing operation and transfer it to the breasting cutter.

94. In a machine of the class described, relatively movable compressing molds, means for presenting a heel after compression over the molds, heel breasting means, heel feeding means arranged to engage opposite sides of the heel so presented, and operating connections to cause the feeding means to advance the heel toward the breasting means.

95. In an organized power driven machine for compressing and breasting heels

automatically in a continuous operation, the combination with means for delivering each compressed heel in a predetermined position, of means for transferring each heel from 5 said position, to breasting position including a plurality of intermittently and successively operating devices which take the heels in turn and present each heel in breasting position.

10 96. In a machine of the class described, heel compressing means, an ejector for presenting a heel after compression above the compressing means, heel transferring means mounted for movement transversely of the 15 heel to engage it and longitudinally of the heel to transfer it, operating connections for said transferring means, and means for treating the heel after transference.

97. In a machine of the class described, 20 heel compressing means, heel breasting means, a table along which the heel is to slide on its way to the breasting means, means for presenting a compressed heel above said table, and means for sliding the 25 heel along the table toward the breasting means, said breasting means being constructed and arranged to breast the heel while its tread face remains parallel to the plane of said table.

30 98. In a machine for operating on shoe bottom blanks, the combination of a blank support, and positioning members relatively power operated in the operation of the machine and acting respectively on the said 35 blank to determine its longitudinal position and orientation.

99. In a machine for operating on shoe bottom blanks, the combination of a blank support 160, and positioning members 120, 40 180 relatively power operated in the operation of the machine and acting respectively on said blank to determine the one its longitudinal position and the other its orientation.

45 100. In a machine for operating on shoe bottom blanks, the combination of operating means, means for locating the blank longitudinally, and means automatically power operated to engage an edge face of the blank 50 at a plurality of points spaced transversely thereof, and acting to aline the blank relatively to the operating means.

101. In a machine for operating on shoe bottom blanks, the combination of operating 55 means, a relatively movable locating members one to determine the longitudinal position of the blank and the other to determine the direction of its longitudinal median line, and means for relatively actuating said 60 members to orient the blank prior to the operation of the operating means.

102. In a machine of the class described, 65 blank positioning means comprising means for holding a blank against translational movement in the plane of the blank, means

for engaging a straight edge of the blank on opposite sides of its longitudinal median line, and means for effecting movement of the edge engaging means to effect orientation of the blank. 70

103. In a machine of the class described, blank positioning means comprising means for holding a blank against translational movement in the plane of the blank, means for engaging an edge of the blank on opposite sides of its longitudinal median line, and power operated means for effecting movement of the edge engaging means against the blank to locate its longitudinal median line in a predetermined direction. 75

104. In a machine for operating upon shoe bottom blanks, the combination of a support for one of the largest surfaces of the blank, means movable perpendicularly to the support to operate upon the blank, means engaging a straight edge face of the blank at separated points, and means for locating another portion of the blank in predetermined position, said edge engaging means acting upon actuation thereof longitudinally of the 90 blank to orient the blank, and connections automatically to operate said edge engaging means. 85

105. In a machine for operating upon shoe bottom blanks, the combination of a support 95 for one of the largest surfaces of the blank, means to operate upon the blank, means engaging a straight edge face of the blank at separated points, means for engaging a curved edge portion of the blank to determine its longitudinal position, and means for operating said edge engaging means prior to operation of the operating means to position the blank longitudinally against said curved edge engaging means and to orient said blank 100 for the said operation. 105

106. In a machine for treating shoe bottom blanks, the combination of means for engaging opposite edges of the blank, other means for engaging another edge of the blank 110 at separated points, and power operated means for relatively operating said two means to cause the blank to turn against the holding power of the means engaging opposite edges and to become oriented with respect to the other engaging means. 115

107. In a machine for treating shoe bottom blanks having partly straight and partly curved edges, means for holding a blank by pressure against opposite curved edges, 120 means having separated points of contact for engaging the straight edge, and power operated means for effecting relative movement between said edge engaging means to effect definite orientation of the blank with respect to its straight portion. 125

108. In a machine for operating on heels, the combination of means for operating on a heel breast, means for approximately locating the heel with respect to the operating 130

means, and means having a power effected operative movement against the heel to ensure complete alinement of the heel breast relatively to the operating means prior to 5 operation of said means upon the heel.

109. In a machine of the class described, heel supporting means, heel locating means, heel breasting means, means for effecting relative movement between the breasting 10 means and the supporting means to breast the heel, and means having an operative movement against the heel breast prior to the breasting operation to ensure alinement of the heel with the breast- 15 ing means.

110. In a machine of the class described, the combination of heel supporting means, heel locating means, a breasting knife, and spring actuated means normally withheld 20 from the heel and controlled in time relation to the breasting operation to cause it to engage the breast of the heel and position the heel with its breast face substantially parallel with the plane of the knife.

25 111. In a machine of the class described, the combination with a heel support and a breasting knife between which there is relative movement to breast the heel, of means for presenting the heel to the knife, and means 30 operated in time relation to said relative movement and prior to commencement of the breasting operation to engage the heel and shift its breast face into alinement with the plane of action of the knife if it is out of 35 alinement.

112. In a machine of the class described, the combination with a heel support and a breasting knife between which there is relative movement to breast the heel, of a heel 40 alining device spring actuated toward the heel to engage the heel breast, and cam means controlling actuation of the device in time relation to the breasting operation.

45 113. In a machine for treating heels, a plurality of mechanisms for performing successive operations upon the heels, oscillating means, and an endless conveyor, said oscillating means acting to remove a heel from an operating mechanism after its operation 50 and to present the heel to the conveyor and said conveyor acting to transfer the heel to another operating mechanism.

55 114. In a machine for treating unattached heels, the combination of cutting means, a heel support to cooperate with the cutting means, a rotary transerrer to take a heel from receiving position and present it between the support and cutting means, and means for relatively operating the support 60 and cutting means to treat the heel.

115. In a machine of the class described, the combination of mechanism for removing surplus material from a heel, mechanism for compressing the heel, and means 65 independent of said mechanisms for trans-

ferring the heel from one of said mechanisms to the other including a spider arranged for uni-directional rotation and having jaws to hold the heel while in transit. 70

116. In a machine of the class described, the combination of mechanism for removing surplus material from a heel, mechanism for compressing the heel, and means for transferring the heel from one of said mechanisms to the other including a rotating 75 spider having separate pairs of relatively movable jaws for holding and transferring successive heels.

117. In a machine of the class described, the combination of mechanism for removing 80 surplus material from a heel, mechanism for compressing the heel, and means for transferring the heel from one of said mechanisms to the other including relatively movable jaws arranged to carry the heel in 85 a horizontal plane in its movement from one mechanism to the other.

118. In a machine of the class described, the combination of mechanism for removing 90 surplus material from a heel, mechanism for compressing the heel, and means for transferring the heel from one of said mechanisms to the other including a rotating spider having a plurality of pairs of jaws, 95 said pairs operating successively to hold a heel by engagement with its side and to advance the heel during its transfer from one mechanism to the other.

119. In a machine of the class described, the combination of mechanism for removing 100 surplus material from a heel, a series of pairs of yieldingly closed jaws, means for moving the series intermittently to locate each pair successively in a receiving station, an operating station and a discharging station, and means for opening each pair of jaws while at rest at the first station to receive a heel and at the last station to discharge it.

120. In a machine for breasting unattached heels, the combination of a breasting knife, a cutting block relatively to which the knife is moved to breast the heel, a carrier for the heel, and means constructed and arranged to operate the carrier to cause the 115 breast end of the heel to be presented over the cutting block.

121. In a machine for breasting heels, the combination of a reciprocating breasting knife, a stationery cutting block to support 120 the heel for the action of the knife, a carrier movable toward and from the block arranged to receive a heel when in a position away from the block and when in another position to present the heel with its breast end resting on the block in position to be breast, and power means for operating the carrier and knife in timed relation to present the heel in breasting position and then breast the heel. 125

122. In a machine for breasting heels, the combination of a reciprocating breasting knife, a stationary cutting block to support the heel for the action of the knife, a carrier 5 movable toward and from the block arranged to receive a heel when in a position away from the block and when in another position to present the heel with its breast end resting on the block in position to be breasted, 10 and means for positioning and holding the heel in the carrier, and power means for operating the carrier and knife in timed relation to present the heel in breasting position and then breast the heel.
123. In a machine for breasting heels, a breasting knife and a heel support relatively operated to breast a heel, heel transferring means for presenting a heel breast-forward in breasting position on the support, and 20 means engaging the heel breast at laterally separated points of the breast face for aligning the heel breast with the breasting knife prior to the relative action of the knife and support to breast the heel.
124. In a machine for breasting heels, the combination of breasting means, a stationary block for supporting the heel for the action of the breasting means, a heel carrier for presenting the heel in breasting position on the block, means to locate the heel in predetermined relation to the carrier, and means for holding the carrier against movement during the operation of the breasting means.
125. In a heel breasting machine, heel 35
- breasting means, heel transferring and positioning means including means engaging the sides of the heel adjacent to the breast, and means engaging the opposite ends of the heel to locate the heel longitudinally and transversely with respect to the breasting means.
126. In a machine for breasting unattached heels, the combination of breasting means, power operated heel transferring means acting to receive a heel in a position 40 remote from the breasting means and to transfer the heel into operative relation to the breasting means, heel locating means acting by equal and opposite movement on the sides of the front portion of the heel to 45 locate the heel laterally, and means engaging the heel breast to locate the heel longitudinally.
127. In a machine of the class described, the combination of breasting means, a stationary support to sustain the heel for the operation of the breasting means, heel transferring means acting to move the heel from a position remote from the breasting means 50 into position on its support in operative relation to the breasting means, heel locating means acting by equal and opposite movement against the sides of the front portion of the heel to locate the heel laterally, and means engaging laterally separated points 55 of the heel breast to locate the heel longitudinally.

In testimony whereof I have signed my name to this specification.

THOMAS LUND.
